Baldwin, N. Y.

Application October 11, 1938, Serial No. 234,337

2 Claims. (Cl. 211—90)

This invention relates to corner shelves, and more particularly to a shelf which is adapted to be placed in the corner of the room or in any portion thereof where there is an angular construction.

In the past difficulty has been met in placing shelves in the corners or other angular portions of rooms and it has been necessary to construct individual shelves to meet particular requirements.

10 The uses of such shelves has a tendency to mar plaster and woodwork unduly, and in many instances the screws or nails by which they are held in place have caused the plaster or composition wall to crumble or chip.

15 An object of this invention is to provide as an article of manufacture a corner shelf which is suitable for use in any corner or angle of the room, which may be easily erected, and which makes provision for the use of any type of molding which may be desired. A further object is to provide a shelf adapted to support ornaments or other articles such as clocks, and which is so constructed that the clocks, vases or other similar articles may be placed on the shelf and

25 detachably fastened in place.

A further object of this invention is to provide a shelf of the character described which is economical to manufacture and which may be sold to the ultimate consumer at the lowest cost.

30 With these and other objects in view, which will appear as the description proceeds, reference is had to the accompanying drawing, in which—

Fig. 1 is a plan view of our improved shelf in place;

Fig. 2 is a cross-sectional view taken on the line 2—2 of Fig. 1 and showing an object detachably fastened to the shelf;

Fig. 3 is a cross-sectional view on the line 3—3 of Fig. 1 showing the manner in which the molding is held in place;

Fig. 4 is a detailed sectional view showing the manner of constructing fastening means; and

Fig. 5 shows a modified form of fastening means.

We provide a shelf body 10 made out of metal or other suitable material. While the shelf shown in the drawing is right angular and adapted to a right angle corner, it will be appreciated that it could be constructed to fit any corner not right angular. The shelf 10 is provided on either side with one or more prongs 11 which are adapted to be driven in and inserted into a wall 12 when the shelf is put in place.

55 The inner part of the shelf is bent downwardly

to form an ear 13 which performs two functions. The ear 13 is provided with a hole 14 through which a nail 15 may be driven into the corner to further secure the shelf. The ear 13 likewise provides an opening 16 at the bottom and innermost corner of the shelf to allow passage of an electric wire should a lamp or clock be used on the shelf.

5 A molding 17 is also provided for the outer edge of the shelf 10. This molding may be of any suitable nature to match the woodwork or walls of the room and is cut with an angular end 18 to fit the wall. Molding 17 is provided with a groove 19 adapted to engage the edge 20 of the shelf 10. The edge 20 of the shelf 10 is provided with obstruct tongues 21 triangular in shape and having their inner point toward the back of the shelf.

10 The shelf is also provided with a key slot 22 to hold a clock, vase or similar article 23 in place on the shelf. As shown in Fig. 2, the object to be placed on the shelf is provided with a screw or rivet 24 having an extending head 25 which may be inserted through the larger portion 26 of the key slot and then moved forwardly to hold it in place. While this would not be necessary in the normal shelf yet where the shelf is used in boats or similar constructions it is highly desirable.

15 In constructing the shelf the triangular shelf 10 itself is cut out. A cut 27 is then made on the sides thereof and a wedge driven into this cut to cause the prong 11 to extend outwardly. In the modified form in Fig. 5, the prong 28 is cut out when the shelf is cut out of the piece and extends outwardly. The prong 11 may have a sharpened edge 29 and a point 30 to form a firmer and more easily applied fastening means. The tongues 21 are then struck up along the edge 20, the ear 13 folded downwardly, and the key slot 22 inserted.

20 It will be appreciated of course that in actual manufacture the entire construction will be performed in one operation with a proper cutting die. The shelf is then ready for insertion into the corner and is inserted merely by placing it in the desired position and tapping the edge 20 of the shelf, driving the prongs 11 into the wall. If desired the nail 15 may be inserted although this is not essential. The molding is then tapped on with the hand to the edge 20. The position 25 of the tongues 21 is such that the molding will be firmly held by them. While we have shown two prongs on either side of the shelf, it will be appreciated that one or more prongs could be used depending upon the size of the shelf and

the nature of the wall on which it is to be used.

This construction is a sturdy shelf which will hold considerable weight. If it is so desired, the molding **17** may be left off and an object having rivet or hook **24**, which would extend over the shelf and downwardly, may be placed on the shelf covering the edge **20**.

We claim:

- 10 1. A shelf comprising a triangular portion, outwardly extending prongs integral with said shelf on two edges of said shelf adapted to engage a wall, means on said shelf for holding articles in

place, said means comprising a key slot, a slot molding on the outward edge of said shelf, and means on said shelf to engage the slot in said molding to hold it in place.

2. A corner shelf comprising a triangular piece 5 of metal, prongs on two sides of said shelf, said prongs being formed integral with the shelf and extending parallel to the central axis of the shelf whereby said prongs will move into a supporting wall in a direct line with the force necessary to 10 install said shelf.
